GROMMET FORMING MACHINE

William M. Young, College Point, N. Y., assignor
to Echo Gasket Mfg. Corp., New York, N. Y., a
corporation of New York

Application April 1, 1949, Serial No. 84,801

2 Claims. (Cl. 57—21)

1

This invention relates to grommet forming machines.

It is an object of the present invention to provide a grommet forming machine wherein flexible rope-like material can be twisted into a round grommet wherein the mandrel can be positively driven to pull the rope-like material through the twisting elements and to positively return the same at the end of the stroke by the connection of a drive returning member with the mandrel.

It is another object of the present invention to provide with a grommet making machine a device for placing the rope-like material into a twisted shape before it is applied to the mandrel wherein a common drive and common foot control mechanism is utilized for both the mandrel and the twisting of the length of rope material and wherein the return of the mandrel can be effected upon the depressing of the foot lever to effect the twisting of the length of material.

Other objects of the present invention are to provide a grommet making machine which is of simple construction, easy to operate, inexpensive to manufacture, semi-automatic, positively driven parts, adequate guiding rods for the mandrel, simple control mechanism and efficient in operation.

For other objects and for a better understanding of the invention, reference may be had to the following detailed description taken in connection with the accompanying drawing, in which

Fig. 1 is a plan view of the grommet forming machine embodying the features of the present invention.

Fig. 2 is a fragmentary perspective view of a portion of the machine.

Fig. 3 is a vertical sectional view taken through the rollers for the operation of the mandrel.

Fig. 4 is a fragmentary transverse sectional view taken on line 4—4 of Fig. 1.

Fig. 5 is a fragmentary longitudinal sectional view taken on line 5—5 of Fig. 1.

Fig. 6 is a longitudinal sectional view taken on line 6—6 of Fig. 1.

Fig. 7 is a plan view of the grommet.

Referring now to figures, 10 represents a table on which the various parts of this apparatus are mounted. At the rear of the table are upstanding bearing brackets 11, 13 and 14 for rotatably supporting a main drive shaft 15 having a large pulley 16 on one end thereof connected by a belt 17 with an electric motor 18. A large pulley 19 is fixed to the shaft through which belts 21 and 22 are connected. The belt 22 is twisted to

obtain reverse rotation of an upper shaft at 23 journalled on a bearing bracket 24 extending forwardly from the front edge of the table. A shaft 25 is journalled on the bracket 24 below the shaft 23 and is driven by the belt 21. The belt 22 runs over pulley 26 whereas the belt 21 runs over pulley 27 on the lower shaft 25. On each of these shafts are rubber driving rollers 28 and 29 respectively. These rollers are grooved and through them runs an elongated rubber mandrel 31 on which a grommet is formed. Guide rods 32 and 33 extend forwardly from the bracket 24 and are supported at the rear of the table by upstanding brackets 35 and 36. The mandrel has a forwardly extending extension 37 which is screw-threaded upon the main body of the mandrel as indicated at 38. The outer end of the extension has a ball bearing element 39 secured thereto, Fig. 5, and this element is supported in a movable slide 41. A twisted shaft 42 is secured to the forward end of the extension 37 by a threaded projection as indicated at 43. The end of the spiral extension 42 passes through a square opening in a plate 44 whereby, as the mandrel and its extensions are pulled rearwardly, a rotation will be given to the mandrel so that the rope-like material will be wound upon the mandrel in one direction while a twisting operation is being effected with the rollers 28 and 29. The slide 41 is pulled rearwardly by two chains 46 and 47 connected to winding elements 48 and 49, respectively, on the shaft 15. These members 48 and 49 are held rigidly connected with one another by a spacing element 50 and are slidable toward a clutch or brake element 51 fixed to the shaft 15 for rotation. The rotation of this element 51 is damped by a spring pressed braking element or bracket 52, Figs. 1 and 6, engaging with the braking surface of the element. To effect the rearward movement of the slide 41, the elements 48 and 49 are pressed against the clutching element 51 by a linkage indicated generally at 54 pivoted on the table and operated by a chain 55, Fig. 2, which extends over a pulley 56 and is connected with a foot lever 57 pivoted on a shaft 58 supported on the floor by journal brackets 59 and 60. A return chain 62 with a spring 63 is connected between a projection 64 on the bracket 24 and the foot lever 57 whereby to return the foot lever to the raised position. The rear end of the spiral extension is supported on a roller 65, Fig. 1. Stop devices 66 with springs 67 are provided on the opposite ends of the rods 32 and 33.

In order that the rope material can be prop-

erly prepared for the forming of the grommet, there is provided a spindle 71 mounted on a bracket 72 and adapted to be operated by a belt 73 connected with a large pulley wheel 74 on the driving shaft 15. This spindle 71 has a transverse member 75 to which the rope material is connected and while retaining the free ends of the rope material in the manner illustrated in Fig. 1, the material will be twisted and pre-formed. The rotation of the spindle 71 is controlled by a foot lever 77 pivoted on the shaft 58 and is connected by a chain 78 to a pivoted lever 79, Fig. 2, which will normally keep a clutch element 81 out of engagement with the pulley belt 73 due to the action of the spring 82. When the lever 77 is depressed, the action of the spring is overcome and a spring 83 on the spindle shaft 71 will urge the clutch element 81 into engagement with the pulley.

Pivoted on the front of the table is a lever 85 which is connected to a chain 86. This chain 86 is connected to the foot lever 77 whereby as the foot lever 77 is depressed the lever 85 will be pivoted in a counter-clockwise direction as shown in Fig. 2 so as to elevate a rod 87 having a wheel 88 thereon. The rod 87, when released, will be returned to an adjustable stop 89. The wheel 88 can engage with the mandrel 31 and by connection with the roller 29 cause the mandrel to be withdrawn after it has been extended forwardly to form the grommet. The twisted strands of rope material can be placed upon the spindle in the manner as shown in Fig. 3, and as the operator steps on the foot lever 77, the mandrel will be drawn along with the rope material so as to cause the rope material to be passed between the rollers which will effect a twisting action upon the same and eventually form the grommet as shown in Fig. 7. Once the grommet has been formed, the operator will step upon the lever 77 and cause the roller 88 to be elevated for engagement with the mandrel 31 so as to effect a return motion of the mandrel with the grommet. The grommet can be pulled from the mandrel. The same lever 77 is used for the initial twisting of the rope material as shown in Fig. 1.

It should now be apparent that there has been provided a grommet forming machine which is of simple construction and which is of sufficient

flexibility to permit the easy formation of a grommet of rope material and that such a machine has a simple control arrangement whereby the hands can be made free while the various devices are operated by the feet. An electric switch 91 controls the electric motor 18.

While various changes may be made in the detail construction, it shall be understood that such changes shall be within the spirit and scope of the present invention as defined by the appended claims.

Having thus set forth and disclosed the nature of my invention, what is claimed is:

1. A grommet forming machine comprising a table, a constantly driven shaft, operating rollers spaced one above the other and pulley belt means connecting said rollers with said shaft to effect the reverse operation of the rollers, a mandrel operable between the rollers, a member fixed to the table and having a square opening therein, said mandrel having a spiral extension thereon adapted upon engagement with the square opening in the member to cause the mandrel to be turned, guide rods on the opposite side of the mandrel, a slide connected to the mandrel and to the guide rods to slide over the guide rods, releasable means connected to the slide and to the constantly driven shaft for effecting the movement of the mandrel, said mandrel being rotatable in the slide and a lever arrangement connecting with the releasable means for controlling its operation.

2. A grommet forming machine as defined in claim 1 and a return device for the mandrel comprising a vertically adjustable member having a roller thereupon and adapted when elevated to engage with the mandrel to cause its return movement and with one of the twisting rollers to be powered therefrom.

WILLIAM M. YOUNG.
